PROCESS OF OBTAINING ABSOLUTE ALCOHOL

Filed April 5, 1921

UNITED STATES PATENT OFFICE.

JOHN A. STEFFENS, OF BALTIMORE, MARYLAND, ASSIGNOR TO U. S. INDUSTRIAL
ALCOHOL CO., A CORPORATION OF WEST VIRGINIA.

PROCESS OF OBTAINING ABSOLUTE ALCOHOL.

Application filed April 5, 1921. Serial No. 458,833.

My invention relates particularly to a process designed to obtain alcohols having a high strength by removing water from the same but it has especial reference to the 5 production of absolute alcohol.

The object of my invention is to provide a process whereby alcohols may be separated from water and especially by means of which absolute alcohol may be obtained in 10 accordance with a commercially practicable system.

More particularly, the object of my invention is to provide a process based upon the utilization of a third liquid which is miscible with the alcohol but substantially immiscible with water and which is of such a character that when the three constituents are present vapors of the same are evolved by distillation containing a considerable 20 percentage of water and the third liquid so that all the water and the third liquid may be removed in this way from the residual constituent, which is the alcohol. The evolved vapors are comprised of a ternary mixture of the three constituents. This third liquid may be of any one of a number of different compounds, such, for example, as benzol, carbon tetrachloride, hexane, etc., but I prefer to use benzol.

One of the objects of my invention is to avoid the necessity of using a large amount of benzol in carrying out the process.

A further object is to so arrange the process as to enable a close regulation thereof to be obtained, inasmuch as in my process the dehydration of the alcohol is carried out in a column, the upper portion of which is fed continually with a quantity of the condensate of fixed composition passing out 35 of the top of the tower, as a condensate rich in water is obtained with a comparatively small load being placed upon the auxiliary apparatus and as the alcohol evolved in the form of vapor is returned to the tower continually in the form of a liquid having a fixed composition obtained by a uniform rectification of the recovered alcohol.

Another object is to operate the process 50 so that a drier benzol is obtained owing to the separation of the condensate before introducing water into the same.

A further object is to so arrange the system as to enable the several operations to 55 be carried out continuously, but so that

the several operations may be carried out largely independently of the remaining operations, thus enabling the operator of the system to recover in case at any time any one of the operations does not function. 60 This is brought about especially by reason of the complete removal of the benzol from the distillate prior to the rectification of the dilute alcohol. By reason of these features in my process the system may be operated 65 continuously.

Further objects will appear from the detailed description thereof contained herein-after.

While my invention is capable of embodiment in many different forms, for the purpose of illustration I shall describe only certain ways in which my invention may be carried out, and while my invention is capable of being carried out in connection with 70 many different types of apparatus, I have shown only one form of the same in the accompanying drawings, in which—

The figure is a diagrammatic representation of an apparatus which may be used 80 in connection with my invention.

In the drawings, I have shown a valved inlet pipe 1 for feeding continuously into the apparatus an alcohol mixed with water, and which, by way of example, may feed to 85 the system ethyl alcohol having a strength of 95%. Leading into the pipe 1 there is a valved supply pipe 2 for supplying initially the desired quantity of the third liquid, as, for example, benzol, and for supplying to 90 the system additional amounts of benzol to replace the small quantities thereof which are lost by evaporation therefrom. The alcohol and benzol are fed to the system in proportions such that in the circulating system, at any given time, there would be approximately equal parts by weight of 95% alcohol and benzol but preferably a slightly smaller quantity of the benzol than of the 95% alcohol. The valved pipe 1 leads into 95 a tail-box 3 which is connected by a liquid sealed pipe 4 to a dehydrating column 5 which is constructed in any suitable manner but which may have, for example, a plurality of plates the same as in the case of the usual alcohol rectifying column. The column 5 has at the bottom an inlet 6 and an outlet 6^a for steam for heating the column indirectly. Vapors are evolved from the column comprising approximately 74.1% by 100 110

weight of benzol, 7.4% by weight of water, and 18.5% by weight of alcohol and absolute alcohol flows from the liquid sealed outlet pipe 7. The evolved vapors pass out by means of a pipe 8 into a dephlegmator 9 which is connected by a liquid sealed pipe 10 to the top plate of the column. The dephlegmator is cooled in the usual way with the aid of water inlet and outlet pipes 11 and 12. The uncondensed vapors from the dephlegmator 9 pass into a condenser 13 through a pipe 13* the temperature in which is at approximately 64.9° C., said condenser being cooled by water passing through inlet and outlet pipes 14 and 15 and the condensate therefrom enters a vented sight-glass 16 from which a portion of the condensate passes through a valved pipe 17 to the pipe 10 and thence to the top of the column 5. The main portion of the condensate is conducted by a pipe 18 to a tail-box 19 and thence by a pipe 20 to a separating chamber 21. The liquid received in the separating chamber immediately separates into two liquid phases forming layers, the upper layer of which is rich in benzol but poor in alcohol and water, while the lower layer is rich in alcohol and water but poor in benzol. The composition of the respective layers is approximately as follows: The upper layer contains approximately 85.6% by weight of benzol, 2.8% by weight of water, and 11.6% by weight of alcohol, while the lower layer contains approximately 8.1% by weight of benzol, 40.6% by weight of water, and 51.3% by weight of alcohol. The upper layer is conveyed by a vented pipe 22 having a liquid seal 23 back to the tower 5 while the lower layer passes by a vented pipe 24 to a scrubber 25. In order to remove the remainder of the benzol, water is introduced into the scrubber 25 by a pipe 26 thus producing therein two layers of liquid, the upper layer of which contains the remainder of the benzol. The benzol layer is conducted from the scrubber by a vented pipe 27 to the liquid seal 23 and thence to the tower 5, while the lower layer is conveyed through a vented liquid sealed pipe 28 to an alcohol rectifying column 29 having a steam inlet pipe 30 and an outlet 30* in the usual way for indirect heating and a liquid sealed drawoff pipe 31 for water at the bottom of the column. The lower portion of the column 29 is maintained at a temperature just above 100° C. The evolved alcohol vapors containing some water pass out of the top of the column through a pipe 32 to a dephlegmator 33, constructed substantially the same as the dephlegmator 9 and which is arranged to return the condensate therein to the top of the column 29 by a liquid sealed pipe 34. The vapors from the dephlegmator 33 pass through a pipe 35, the vapors in which are at a temperature of approxi- mately 76° C., to a condenser 36 constructed the same as the condenser 13. The condensate from the condenser 36, which comprises approximately 95% alcohol enters a vented sight-glass 37 and a portion of the same passes back through a valved pipe 38 to the liquid sealed pipe 34 and thence to the top of the column 29, while the remainder thereof enters a tail-box 39 and is conveyed therefrom by a valved pipe 40 direct to the liquid sealed pipe 23 and thence to the column 5. The apparatus is also arranged in an effective manner in that the portions thereof requiring observation are located upon an operating floor 41.

In carrying out my invention, the alcohol containing water and the benzol is fed into the column 5 the lower portion of which is maintained at a temperature slightly below 78.4° C. The vapors of alcohol, water and benzol will be distilled from the top of the column 5 thus leaving behind absolute alcohol which passes out of the bottom of the column through the pipe 7. The evolved vapors pass into the dephlegmator 9, whence some of the condensate is returned to the topmost plate in the column 5 and at the same time a small portion of the condensate from the condenser 13 is also conveyed into the tower at the same point, thus sealing the uppermost plates in the column with a liquid of a constant composition and which is very close to the composition of the evolved vapors. This not only provides uniform conditions at the top of the tower but enables the process to be conducted with a comparatively small quantity of benzol so that the condensate reaching the separating chamber 21 will be rich in the water to be removed. When the liquid condensate reaches the separating chamber 21 it immediately divides into two layers, the upper layer, comprised principally of benzol, being conveyed back to the tower 5, while the lower layer, comprised principally of alcohol and water but containing some benzol, is conducted to the scrubber 25 where water is added in the proportions of approximately one part by weight of water to one part by weight of the incoming liquid. This separates out the benzol into an upper layer which is conveyed back to the column 5, while the dilute alcohol is conducted to the alcohol rectifying column 29. This column is required merely to rectify the alcohol, said column at its lower portion being maintained at a temperature of approximately 100° C., the water from which passes out from the bottom of the column, while the alcohol substantially 95% in strength is collected as a condensate having a fixed composition and temperature which is returned to the column 5. Inasmuch as the alcohol returned to the column 5 has a definite composition and temperature, and as the benzol

has been substantially entirely removed therefrom, the conditions in the upper portion of the column 5 are comparatively uniform so far as the character of the incoming alcohol is concerned. Furthermore, inasmuch as the bulk of the benzol is returned directly from the separating chamber 21 to the column 5, while the scrubbing is applied only to the small portion of the benzol 5
10 covered in the scrubber 25, the benzol is returned to the column 5 in a drier form than would otherwise be the case and this also conduced to uniformity in the operation of the process. For the same reason less water 15 is carried back into the column 5 and there is consequently a more effective separation of the alcohol from the water. By providing a system of this character in which the several parts of the system operate without 20 a great degree of dependence upon one another it is possible to conduct the process with great uniformity of results and in such a way that the failure of any portion of the system to function temporarily would not 25 interfere with the effective operation of the system as a whole. For these reasons, furthermore, it is practicable to obtain absolute alcohol with the process continuously.

While I have described my invention 30 above in detail I wish it to be understood that many changes may be made therein without departing from the spirit of the same.

I claim:

1. The process of obtaining absolute alcohol which comprises distilling in a column a mixture of an alcohol, water, and a third liquid miscible with the alcohol but substantially immiscible with water, to form 40 a constant boiling mixture and to obtain absolute alcohol at the bottom of said column, condensing a part of the evolved vapors and returning it to the top of the column, and separating the constituents of the 45 remainder of the said vapors.

2. The process of obtaining absolute alcohol which comprises distilling in a column a mixture of an alcohol, water, and a third liquid miscible with the alcohol but substantially immiscible with water to form a constant boiling mixture and to obtain absolute alcohol at the bottom of said column, condensing a part of the evolved vapors and returning it to the top of the column, condensing a further quantity of the vapors and also returning it to the top of the column, and separating the constituents of the 55 remainder of the said vapors.

3. The process of obtaining absolute alcohol which comprises distilling alcohol, water, and a third liquid miscible with the alcohol but substantially immiscible with the water, to form a constant boiling mixture and to obtain absolute alcohol; condensing a portion 60 of the evolved vapors and returning it

to the liquid mixture being distilled; condensing a subsequent portion of the vapors and returning it in part to the said liquid mixture being distilled and washing the remainder with water to separate out said 70 third liquid from the other two constituents.

4. The process of obtaining absolute alcohol which comprises distilling alcohol, water, and a third liquid miscible with the alcohol but substantially immiscible with the water, 75 to form a constant boiling mixture and to obtain absolute alcohol; condensing the evolved vapors and allowing a portion of the condensate to separate into two layers, returning the layer richer in said third 80 liquid to the liquid mixture being distilled, and treating the other layer to remove substantially the remainder of said third liquid, and distilling the remainder of said layer to form high strength alcohol, and returning the latter to the liquid mixture being distilled.

5. The process of obtaining absolute alcohol which comprises distilling alcohol, water, and a third liquid miscible with the alcohol 85 but substantially immiscible with the water, to form a constant boiling mixture and to obtain absolute alcohol; condensing a portion of the evolved vapors and returning it to the liquid mixture being distilled to provide a reflux; condensing a subsequent portion of the vapors and allowing the condensate to separate into two layers, returning the layer richer in said third liquid to the liquid mixture being distilled and treating the other layer to remove substantially the remainder of said third liquid, distilling the remainder of said layer to largely separate aqueous alcohol of high 95 strength from the water, and returning the 100 alcohol to the liquid mixture being distilled.

6. The process of obtaining absolute alcohol, which comprises distilling a mixture of an alcohol, water, and a third liquid miscible with the alcohol but substantially immiscible with water, to form a constant boiling mixture and to obtain absolute alcohol; condensing a portion of the evolved vapors, washing it with water by successive 105 washings to separate the third liquid, and returning the latter to the liquid mixture being distilled.

7. The process which comprises distilling a mixture of an alcohol, water and a third liquid, miscible with the alcohol but substantially immiscible with water, and separating out from the condensed evolved vapors substantially all of the third liquid by allowing the condensate to separate into two liquid layers, washing with water the 110 layer containing the smaller proportion of the third liquid and then returning the third liquid to the liquid mixture being distilled.

8. The process of obtaining absolute alco-

- 4
- hol which comprises distilling alcohol, water, and a third liquid miscible with the alcohol but substantially immiscible with the water, to form a constant boiling mixture and to obtain absolute alcohol; condensing the distillate and allowing a portion thereof to separate into two layers, returning the layer richer in said third liquid to the liquid mixture being distilled, treating the other layer to separate substantially the remainder of said third liquid from the water and alcohol therein and returning this remainder also to the liquid mixture being distilled.
9. The process which comprises distilling a mixture of an alcohol, water and a benzol, and separating out from the condensed evolved vapors substantially all of the benzol by allowing the condensate to separate into two liquid layers, washing with water the layer containing the smaller proportion of the benzol and then returning the benzol to the liquid mixture being distilled.
10. The process of obtaining absolute alcohol which comprises distilling alcohol, water, and a third liquid miscible with the alcohol but substantially immiscible with the water, to form a constant boiling mixture and to obtain absolute alcohol; condensing the evolved vapors and allowing a portion thereof to separate into two layers, returning the layer richer in said third liquid to the liquid mixture being distilled, and treating the other layer to remove therefrom alcohol of approximately 95% concentration, and returning it in liquid form to the liquid mixture being distilled.
11. The process which comprises distilling a mixture of alcohol, water and a benzol, and separating out from the condensed evolved vapors substantially all of the benzol by allowing the condensate to separate into two liquid layers, washing with water the layer containing the smaller proportion of the benzol and then returning the benzol to the liquid mixture being distilled, thereby obtaining absolute alcohol.
12. The process of obtaining absolute alcohol which comprises distilling an alcohol, water, and a third liquid miscible with the alcohol but substantially immiscible with the water, to form a constant boiling mixture and to obtain absolute alcohol; condensing the constant boiling mixture and separating out from a portion thereof the third liquid, distilling the remainder of said portion of the condensate to obtain a more concentrated alcohol, and returning the latter in liquid form to the liquid mixture being distilled.
13. The process of obtaining absolute alcohol which comprises distilling in a column an alcohol, water, and a third liquid miscible with the alcohol but substantially immiscible with the water, to form a constant boiling mixture and to obtain absolute alcohol; condensing the distillate and allowing a portion thereof to flow back as reflux, allowing the remainder of the condensed distillate separate into two layers, returning the layer richer in said third liquid to the upper part of said column below the point of introduction of said reflux but relatively near it.
14. The process of obtaining absolute alcohol which comprises continuously distilling a mixture of an alcohol, water and a third liquid, miscible with the alcohol but substantially immiscible with the water, to form a constant boiling mixture and to obtain absolute alcohol; condensing the evolved vapors and separating a portion thereof so as to remove therefrom substantially all of the third liquid, returning the third liquid to the liquid mixture being distilled, distilling the residue of the said portion of the condensate to obtain therefrom an aqueous alcohol of high strength and returning the same to the liquid mixture being distilled.
15. The process of obtaining absolute alcohol which comprises continuously distilling in a column a mixture of an alcohol, water, and a third liquid miscible with the alcohol but substantially immiscible with the water, to form a constant boiling mixture and to obtain absolute alcohol at the bottom of said column, separating the condensate from the evolved vapors into a major portion and a minor portion, treating said major portion so as to remove therefrom substantially all of the third liquid, returning the latter to the column, distilling the residue of the major portion to obtain therefrom an aqueous alcohol of high strength and returning the same to the first-mentioned liquid mixture being distilled, the minor portion of the condensate being returned to the top of the aforesaid column.
16. The process of obtaining absolute alcohol which comprises continuously distilling in a column an alcohol, water and a benzol, continuously separating the bulk of the condensate obtained from the evolved vapors so as to remove therefrom substantially all of the benzol, returning the benzol to the column, distilling the residue of said bulk of the condensate to obtain therefrom an aqueous alcohol of high strength and returning the same to the first mentioned liquid mixture being distilled, the unseparated portion of the condensate being returned to the top of the first mentioned column.
17. The process of obtaining absolute alcohol which comprises continuously distilling in a column alcohol, water and a benzol, continuously separating the bulk of the condensate obtained from the evolved vapors so as to remove therefrom substantially all of the benzol, returning the benzol to the column, distilling the residue of said bulk of the condensate to obtain therefrom an aqueous alcohol of high strength and returning the same to the first mentioned liquid mixture being distilled, the unseparated portion of the condensate being returned to the top of the first mentioned column.

- ing the same to the first mentioned column, the unseparated portion of the condensate being returned to the top of the first mentioned column.
18. The process of obtaining absolute alcohol which comprises continuously distilling an alcohol, water, and a third liquid miscible with the alcohol but substantially immiscible with the water, to form a constant boiling mixture and to obtain absolute alcohol; separating a portion of the condensate obtained from the evolved vapors so as to remove therefrom substantially all of the third liquid, returning the latter to the liquid mixture being distilled, distilling the residue of said portion of the condensate to obtain therefrom a more concentrated alcohol, and returning the same to the first-mentioned liquid mixture being distilled.
19. The process of obtaining absolute alcohol which comprises distilling an alcohol, water, and a third liquid which is miscible with the alcohol but substantially immiscible with water, to form a constant boiling mixture and to obtain absolute alcohol; condensing a portion of the evolved vapors and separating therefrom an aqueous alcohol substantially free from the third liquid, rectifying it so as to obtain an aqueous alcohol of higher strength and returning the latter in liquid form to the liquid mixture being distilled.
20. The process of obtaining absolute alcohol which comprises distilling in a column an alcohol, water, and a third liquid which is miscible with the alcohol but substantially immiscible with water, to form a constant boiling mixture and to obtain absolute alcohol at the bottom of said column; condensing a portion of the evolved vapors and separating therefrom an aqueous alcohol substantially free from the third liquid, rectifying it so as to obtain an aqueous alcohol of higher strength, and returning the latter in liquid form to the top of the column.
21. The process of obtaining absolute alcohol which comprises distilling in a column an alcohol, water, and a third liquid that is miscible with the alcohol but substantially immiscible with water, to form a constant boiling mixture and to obtain absolute alcohol at the bottom of said column; condensing the vapors evolved and returning part thereof to the top of the column, separating from the remaining condensate an aqueous alcohol substantially free from the third liquid; rectifying it so as to obtain an aqueous alcohol of higher strength, and returning the latter to the column below the point of introduction of the aforesaid condensed vapors.
22. The process of obtaining absolute alcohol which comprises distilling in a column an alcohol, water, and a third liquid that is miscible with the alcohol but substantially immiscible with water, to form a constant boiling mixture and to obtain absolute alcohol at the bottom of said column; condensing the vapors evolved and returning part thereof to the top of the column; separating from the remaining condensate an aqueous alcohol substantially free from the third liquid; rectifying it so as to obtain an aqueous alcohol of higher strength, and returning the latter in liquid form to the column below the point of introduction of the aforesaid condensed vapors.
23. The process of manufacturing substantially anhydrous alcohol which comprises distilling an alcohol, water, and a third liquid that is miscible with the alcohol but substantially immiscible with water, to form a constant boiling mixture and to obtain absolute alcohol; separating from the portion of the vapors evolved the third liquid and an aqueous alcohol substantially free from the third liquid; rectifying said aqueous alcohol so as to obtain an aqueous alcohol of higher strength, and returning the latter in liquid form to the liquid mixture being distilled; and also returning the said third liquid to the liquid mixture being distilled.

In testimony that I claim the foregoing, I have hereunto set my hand this 26th day of January, 1921.

JOHN A. STEFFENS.

- ing the same to the first mentioned column, the unseparated portion of the condensate being returned to the top of the first mentioned column.
- 5 18. The process of obtaining absolute alcohol which comprises continuously distilling an alcohol, water, and a third liquid miscible with the alcohol but substantially immiscible with the water, to form a constant boiling mixture and to obtain absolute alcohol; separating a portion of the condensate obtained from the evolved vapors so as to remove therefrom substantially all of the third liquid, returning the latter to the liquid mixture being distilled, distilling the residue of said portion of the condensate to obtain therefrom a more concentrated alcohol, and returning the same to the first-mentioned liquid mixture being distilled.
- 10 19. The process of obtaining absolute alcohol which comprises distilling an alcohol, water, and a third liquid which is miscible with the alcohol but substantially immiscible with water, to form a constant boiling mixture and to obtain absolute alcohol; condensing a portion of the evolved vapors and separating therefrom an aqueous alcohol substantially free from the third liquid, rectifying it so as to obtain an aqueous alcohol
- 15 of higher strength and returning the latter in liquid form to the liquid mixture being distilled.
- 20 20. The process of obtaining absolute alcohol which comprises distilling in a column an alcohol, water, and a third liquid which is miscible with the alcohol but substantially immiscible with water, to form a constant boiling mixture and to obtain absolute alcohol at the bottom of said column; condensing a portion of the evolved vapors and separating therefrom an aqueous alcohol substantially free from the third liquid, rectifying it so as to obtain an aqueous alcohol of
- 25 higher strength, and returning the latter in liquid form to the top of the column.
- 30 21. The process of obtaining absolute alcohol which comprises distilling in a column an alcohol, water, and a third liquid that is
- 35 miscible with the alcohol but substantially immiscible with water, to form a constant boiling mixture and to obtain absolute alcohol at the bottom of said column; condensing the vapors evolved and returning part thereof to the top of the column, separating from the remaining condensate an aqueous alcohol substantially free from the third liquid; rectifying it so as to obtain an aqueous alcohol of higher strength, and returning the latter to the column below the point of introduction of the aforesaid condensed vapors.
- 40 22. The process of obtaining absolute alcohol which comprises distilling in a column an alcohol, water, and a third liquid that is miscible with the alcohol but substantially immiscible with water, to form a constant boiling mixture and to obtain absolute alcohol at the bottom of said column; condensing the vapors evolved and returning part thereof to the top of the column; separating from the remaining condensate an aqueous alcohol substantially free from the third liquid; rectifying it so as to obtain an aqueous alcohol of higher strength, and returning the latter in liquid form to the column below the point of introduction of the aforesaid condensed vapors.
- 45 23. The process of manufacturing substantially anhydrous alcohol which comprises distilling an alcohol, water, and a third liquid that is miscible with the alcohol but substantially immiscible with water, to form a constant boiling mixture and to obtain absolute alcohol; separating from the portion of the vapors evolved the third liquid and an aqueous alcohol substantially free from the third liquid; rectifying said aqueous alcohol so as to obtain an aqueous alcohol of higher strength, and returning the latter in liquid form to the liquid mixture being distilled; and also returning the said third liquid to the liquid mixture being distilled.

In testimony that I claim the foregoing, I have hereunto set my hand this 26th day of January, 1921.
